UNITED STATES PATENT OFFICE.

GEORGE F. NIEMANN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SWITCH SOCKET.

Application filed July 30, 1924. Serial No. 729,011.

My invention relates to switch sockets and more particularly to a switch socket of the push bar type in which a sub-assembly is held in the casing by the push bar.

5 One of the objects of my invention is to provide means for holding the switch mechanism in position to receive the push bar when it is again inserted to hold the sub-assembly in place.

10 Further objects will appear from the description and claims.

In the drawings, in which an embodiment of my invention is shown—

Figure 1 is an axial section of a push bar 15 switch socket;

Fig. 2 is a section on the line 2—2 of Fig. 1;

Fig. 3 is a plan view of the sub-assembly;

Fig. 4 is a section on the line 4—4 of 20 Fig. 2;

Fig. 5 is a section similar to Fig. 1 showing the switch in open position; and

Fig. 6 is a perspective view of a switch assembly.

25 Referring to the drawings in detail, the construction shown comprises a unit shell sheet metal casing 10 and a sub-assembly, shown in Fig. 2, insertable and removable with respect to the casing through the open end thereof and held in place in said casing by the insulating push bar 11 which operates the switch mechanism. This sub-assembly

30 comprises an insulating base 12, shell and center contact members 13 and 14, wiring terminals 15 and 16, and switch mechanism mounted on this insulating base. The switch controls the circuit between the wiring terminal 15 and the center contact member. For this purpose, a pair of relatively stationary U-shaped spring contact members 17 and 18 are provided, one of which is electrically connected with the wiring terminal 15, and the other of which is electrically connected with the center contact 14 by

35 means of the long eyelet member 19. The binding plate of the wiring terminal 15 is held on the insulating base by means of the long eyelet member 20. The other wiring terminal 16 is electrically connected with the shell contact by means of the screw 21.

40 A passageway is provided in the insulat-

ing base 12 to receive the insulating push bar 11 and oppositely disposed openings 22 and 23 are provided in the casing for the passage of this insulating push bar so that 55 the sub-assembly is held in place in this casing by means of this push bar and can be withdrawn upon removal of the push bar through the side of the casing.

The construction is such that the switch 60 mechanism stays in proper position to receive the insulating push bar when it is again inserted. This switch mechanism comprises, in addition to the insulating push bar, a switch frame 24, an oscillatable 65 switch arm 25 of conducting material pivoted on the switch frame 24 by means of the pintles 26, a coil compression spring 27 shiftable back and forth past the dead center to cause oscillation of the switch arm, and a 70 spring-supporting and carrying member 28, surrounded by the compression spring and having one end slidable in an opening 29 in the end of the switch arm and the other received in a notch 30 in the insulating push 75 bar.

In order to hold this switch arm, spring and spring-carrying member in proper position to receive the push bar, when it is again inserted, the spring-carrying member is provided with a T-shaped head, the laterally extending portions 31 of which rest on the switch frame when the push bar is withdrawn. The switch arm is limited in its oscillatable movement by means of the stop 80 lugs 32 on the switch frame.

If it is desired to withdraw the insulating push bar, it is pulled out on the left side as viewed in Fig. 1, the first withdrawal movement causing the spring-carrying member 90 28 to be lifted up slightly to permit it to disengage from the notch 30 in the push bar. Further withdrawal of the push bar allows the spring-carrying member to settle down onto the supporting sides of the switch frame on which it rests until the push bar is again inserted. Upon again inserting the push bar the spring-carrying member rides up the inclined portion 33 of the push bar until it drops again into the notch.

The circuit is from the wiring terminal 15 through the contact 17, switch arm 25,

contact 18, eyelet 19, center contact 14, shell contact 13 and screw 21 to the wiring terminal 16. In operation, when the push bar is moved from one side to the other the 5 spring 27 is compressed and when it is moved past its dead center causes a quick snappy oscillation of the switch arm to make or break the circuit.

While I have shown but one embodiment 10 of my invention, it is obvious that it may be embodied in other forms covered and defined by the appended claims.

Having thus described my invention, what I claim as new and desire to secure 15 by Letters Patent of the U. S. is:—

1. A switch socket comprising an insulating base, receptacle contacts, wiring terminals and switch mechanism mounted on said base, said base with the contacts and wiring 20 terminals being insertable and removable with respect to a casing as a sub-assembly, said switch mechanism comprising (1) a push bar extending transversely through said sub-assembly and serving to hold said 25 sub-assembly in said casing and being removable laterally from said casing to release said sub-assembly for removal from said casing, (2) an oscillatable switch arm, (3) a spring shiftable back and forth to 30 cause said oscillation of said switch arm, and (4) a spring-carrying member extending between said push bar and switch arm, and means whereby when said push bar is withdrawn from said sub-assembly, said spring- 35 carrying member will be held in position to come into operative relation with said push bar when it is again inserted. 85

2. A switch socket comprising an insulating base, receptacle contacts, wiring terminals and switch mechanism mounted on said base, said base with the contacts and wiring 40 terminals being insertable and removable with respect to a casing as a sub-assembly, said switch mechanism comprising (1) a push bar extending transversely through said sub-assembly and serving to hold said 45 sub-assembly in said casing and being removable laterally from said casing to release said sub-assembly for removal from said casing, (2) an oscillatable switch arm, (3) a spring shiftable back and forth to 50 cause said oscillation of said switch arm, and (4) a spring-carrying member extending between said push bar and switch arm, and means whereby when said push bar is withdrawn from said sub-assembly, said spring- 55 carrying member will be held in position to come into operative relation with said push bar when it is again inserted. 100

3. A switch socket comprising an insulating base, receptacle contacts, wiring terminals and switch mechanism mounted on said base, said base with the contacts and wiring 60 terminals being insertable and removable with respect to a casing as a sub-assembly, said switch mechanism comprising (1) a push bar extending transversely through said sub-assembly and serving to hold said 65 sub-assembly in said casing and being removable laterally from said casing to release said sub-assembly for removal from said casing, (2) an oscillatable switch arm, (3) a spring shiftable back and forth to 70 cause said oscillation of said switch arm, and (4) a spring-carrying member extending between said push bar and switch arm, and means whereby when said push bar is withdrawn from said sub-assembly, said spring- 75 carrying member will be held in position to come into operative relation with said push bar when it is again inserted, said push bar being slidable in said switch frame. 110

4. A switch socket comprising an insulating base, receptacle contacts, wiring terminals and switch mechanism mounted on said base, said base with the contacts and wiring 80 terminals being insertable and removable with respect to a casing as a sub-assembly, said switch mechanism comprising (1) a push bar extending transversely through said sub-assembly and serving to hold said 85 sub-assembly in said casing and being removable laterally from said casing to release said sub-assembly for removal from said casing, (2) an oscillatable switch arm, (3) a spring shiftable back and forth to 90 cause said oscillation of said switch arm, and (4) a switch frame on which said arm is pivoted, provided with a rest engaged by said spring-carrying member upon withdrawal of said push bar whereby when said push bar is withdrawn from said sub-assembly, said spring-carrying member will be held in position to come into operative relation with said push bar when it is again inserted. 100

5. A switch socket comprising an insulating base, receptacle contacts, wiring terminals and switch mechanism mounted on said 95 base, said base with the contacts and wiring terminals being insertable and removable with respect to a casing as a sub-assembly, said switch mechanism comprising (1) a push bar extending transversely through said sub-assembly and serving to hold said 105 sub-assembly in said casing and being removable laterally from said casing to release said sub-assembly for removal from said casing, (2) an oscillatable switch arm, (3) a spring shiftable back and forth to 110 cause said oscillation of said switch arm, and (4) a switch frame on which said arm is pivoted, provided with a rest engaged by said spring-carrying member upon withdrawal of said push bar whereby when said push bar is withdrawn from said sub-assembly, said spring-carrying member will be held in position to come into operative relation with said push bar when it is again inserted, said push bar being slidable in said switch frame. 115

6. A switch socket comprising an insulating base, receptacle contacts, wiring terminals and switch mechanism mounted on said 120 base, said base with the contacts and wiring terminals being insertable and removable with respect to a casing as a sub-assembly, said switch mechanism comprising (1) a push bar extending transversely through said sub-assembly and serving to hold said 125 sub-assembly in said casing and being removable laterally from said casing to release said sub-assembly for removal from said casing, (2) an oscillatable switch arm, (3) a spring shiftable back and forth to 130 cause said oscillation of said switch arm, and (4) a switch frame on which said arm is pivoted, provided with a rest engaged by said spring-carrying member upon withdrawal of said push bar whereby when said push bar is withdrawn from said sub-assembly, said spring-carrying member will be held in position to come into operative relation with said push bar when it is again inserted. 135

tween said push bar and switch arm, and (5) a switch frame on which said arm is pivoted, provided with a rest engaged by said spring-carrying member upon withdrawal of said push bar whereby when said push bar is withdrawn from said sub-assembly said spring-carrying member will be held in position to come into operative relation with said push bar when it is again

inserted, said push bar having a notch to 10 receive the end of said spring-carrying member out of which notch said spring-carrying member rides when the push bar is withdrawn.

In witness whereof, I have hereunto subscribed my name. ¹⁵

GEORGE F. NIEMANN.
